UNITED STATES PATENT OFFICE.

ALLEN T. KIRK, OF CHICAGO, ILLINOIS.

ENGINE STARTER.

Application filed January 3, 1922. Serial No. 526,769.

To all whom it may concern:

Be it known that I, ALLEN T. KIRK, a citizen of the United States, and resident of Chicago, in the county of Cook and State of Illinois, have invented a certain new and useful Improvement in Engine Starters, of which the following is a full, clear, concise, and exact description, reference being had to the accompanying drawings, forming a part of this specification.

My invention relates to an electrically actuated starter for an internal combustion engine of any one of the several types commonly used upon automotive vehicles. Generally speaking, the starter comprises an electric motor with which is associated a pinion that is caused to mesh with teeth carried by the flywheel of the engine, when the power of the electric motor is to be utilized for starting the engine, the pinion being moved out of mesh with the flywheel teeth when the engine commences to operate under its own power.

Among its more important objects, my invention contemplates:

1. The provision of an engine starter comprising means for insuring that the circuit of the starting motor is never closed except when teeth of its associated pinion are fully in mesh with the teeth of the flywheel;

2. The provision of an engine starter comprising electromagnetic means for moving the starting motor pinion into positive engagement with the teeth of the flywheel of the engine when the latter is to be started;

3. The provision of an engine starter comprising improved circuit controlling mechanism adapted to insure that electrical energy is supplied to the motor when, and only when, the teeth of the starting motor pinion are fully in mesh with the teeth of the flywheel;

4. The provision of an engine starter comprising electromagnetic means adapted to cause the starter motor pinion to disengage the teeth of the flywheel when the engine is running under its own power; and

5. The provision of an engine starter comprising means under the control of the operator for causing the last-mentioned electromagnetic means to cause the starting motor pinion to disengage the teeth of the flywheel, if, for any reason, the engine fails

to start when the flywheel thereof is subjected to the torque of the starting motor.

In the accompanying drawings illustrating my invention:

Figure 1 is a plan view of an internal combustion engine to which the starter of my invention has been applied;

Figure 2 is a sectional view of the apparatus which controls the starting motor pinion and also insures that the motor circuit is closed when, and only when, the said pinion is in mesh with the teeth of the flywheel;

Figure 3 is a vertical section taken on the line 3—3 of Figure 2, and looking in the direction indicated by the arrows;

Figure 4 is a vertical section taken on the line 4—4 of Figure 2, and looking in the direction indicated by the arrows; and

Figure 5 is a circuit diagram.

Similar characters of reference refer to similar parts throughout the several views.

Referring first to Figure 1, reference letter A represents an internal combustion engine provided with a flywheel B, the flywheel being preferably disposed in a suitable housing C which is formed integral with or otherwise fixed with respect to the crank case of the engine. At D is indicated a dynamo electric machine which is preferably compound wound and need not differ in its construction from electric motors heretofore commonly used. The reference letter E indicates a housing which is conveniently bolted to flywheel housing C. Housing E contains a major portion of the apparatus with which my present invention is particularly concerned.

Referring now to Figure 2, it will be noted that a shaft 10 extends horizontally through housing E. One end of shaft 10 is disposed in proximity to and in substantial alignment with one end of the armature shaft of motor D and is mechanically connected therewith by any suitable form of coupling, indicated at 11. The specific form of coupling shown comprises a comparatively stiff coil spring having one end thereof fixed with respect to the motor shaft and its other end fixed with respect to shaft 10.

Shaft 10 extends through a sleeve 12, said sleeve 12 being keyed or equivalently related to said shaft and being capable of axial movement independently thereof, it be-

ing incapable of rotary movement independently of said shaft. Sleeve 12 is mounted for both axial and rotary movement in bearings 13 and 14, bearing 13 being carried in a suitable bearing boss 13^a which is formed integral with one end of housing E. Bearing 14 is carried by a similar bearing boss 14^a which is carried by a web or intermediate wall 15 which forms part of housing E. The several parts of housing E and the bushings 13 and 14 are preferably formed of nonmagnetic material. Shaft 10 and sleeve 12 are formed of any material suitable for the purpose, for instance, hardened steel. A key 10^a may afford the necessary connection between shaft 10 and sleeve 12, but it will, of course, be understood that, as an alternative construction, the shaft may have a square or other polygonal cross section and fit snugly but slidably in a correspondingly shaped sleeve passage.

Carried by sleeve 12 and keyed upon that end thereof which lies nearest the flywheel, is a pinion 16, the lateral edges of the pinion teeth which lie nearest the flywheel when the pinion is in the position illustrated in Figure 2, being beveled correspondingly to the adjacent lateral edges of the teeth of the flywheel. The pinion normally lies out of mesh with the teeth of the flywheel, but is adapted to be moved in mesh therewith in the manner and by the means presently to be described. A relatively light spring 17 is disposed around shaft 10 and is located between pinion 16 and a shoulder afforded by a washer 17^a which is carried by that end of shaft 10 which lies adjacent the flywheel. Said spring is preferably just stiff enough to prevent the pinion from engaging the teeth of the flywheel when the engine is running under its own power.

Disposed around the bearing boss 13^a and fixed thereon in any suitable manner is an annular magnet core 19, preferably of soft iron, which comprises annular flanges 19^a and 19^b of different diameters, which constitute magnet poles when core 19 is excited by its associated electromagnetic winding indicated at 20. Disposed around bearing boss 14^a is another magnet core 21 which is identical with core 19, but reversely arranged, i. e., the poles 21^a and 21^b of core 21 extend toward the corresponding poles of core 19. Associated with core 21 is a suitable winding indicated at 22.

Carried by sleeve 12 is an annular soft iron structure 23 which constitutes an armature for the electromagnets hereinbefore described. Said armature is incapable of longitudinal movement independently of sleeve 12, but the sleeve is preferably capable of rotary movement with respect to said armature 23. The connection between the sleeve and the armature may consist of a pin 24 carried by the armature and extending tan-

gentially through an annular groove 25 which is formed in the outer surface of the sleeve. It should be borne in mind that the armature 23 may be rigidly attached to the sleeve if desired, although the form of connection shown, or its equivalent, is desirable. When the magnet core 19 is polarized by its associated winding, the armature 23 will be attracted toward said core 19 and the pinion 16 will be moved into mesh with the teeth of flywheel B. When the electromagnetic core 21 is subsequently excited, the pinion will be caused to disengage the flywheel. The circuits including the electromagnetic windings 20 and 22 and suitable devices for controlling said circuits will presently be explained.

I now call attention to the fact that the right end (Figure 2) of housing E carries two pairs of contact blocks 26-26 and 27-27. The contact blocks may be formed of carbon or other suitable material and are here illustrated as being received in contact block holders 28, the latter being formed of conducting material. The contact block holders of each pair are electrically connected by bars or conductors 29-29 and all of the contact blocks are insulated from housing E by insulating material, indicated at 30-30. Blocks 26-26 are electrically connected with a suitable terminal 31 and blocks 27 are connected with a similar terminal 32. As will subsequently appear, one of said terminals 31 or 32 is electrically connected with one of the terminals of motor D, while the other of said terminals 31 or 32 is suitably grounded.

I now call attention to the snap-over switch mechanism which is illustrated in Figures 2 and 3. This mechanism comprises two arms 33^a and 33^b, each of said arms consisting of a pair of side members 34-34 which are preferably formed of insulating material. Each of the side members 34-34 of the snap-over arm 33^a is pivoted at a point intermediate its ends to a rod or shaft 35, which in turn is carried by lugs 36-36 which are conveniently formed integral with the intermediate wall or web 15 of housing E. The side members 34-34 of the lower arm 33^b of the snap-over mechanism are similarly pivoted at points intermediate their ends upon the rod or shaft 35 which is carried by another pair of lugs 36-36.

Each of the side members 34 of the upper arm 33^a of the snap-over mechanism is provided at its lower end with a pin 37 which engages in a slot 38 in the upper end of the adjacent side member 34 of the lower arm of the snap-over mechanism. Those ends of the pin 37 which lie next adjacent the sleeve 12 are provided with rollers 39-39, the purpose of which will presently appear. The free ends of the side members 34-34 of each arm of the snap-over mechanism are

connected by a rod or shaft 40. Each of said rods 40 passes through ears 41-41 which are secured to or formed integral with the insulating supports 42, which in 5 turn carry conductor bars 43. Corresponding ends of the rods 40 are connected by tension springs 44-44. It will be understood that when the rollers 39 lie in the positions illustrated in Figure 2, the springs 10 44-44 tend to hold the conductor bars 43-43 out of engagement with contact blocks 26 and 27. However, when the rollers 39-39 are moved to the left (Figure 2), to such an extent that they lie to the left of a 15 straight line passing through the rods 40-40, the springs 44-44 will throw the conductor bars 43-43 into engagement with contact blocks 26 and 27, thus establishing electrical connection between terminals 31 20 and 32 (Figure 4).

I now call attention to the fact that the right end of sleeve 12 (Figure 2) is reduced in cross section to provide an annular shoulder X. Spaced from shoulder X and fixed 25 to the smaller diameter portion of sleeve 12 is a ring XX. The shoulder X and the ring XX, by their co-operation with the rollers 39-39, serve to actuate the snap-over switch mechanism.

Let us now refer to the circuit diagram of Figure 5. At 60 I have illustrated a pedal switch which is located adjacent to the driver's position. The spring 61 normally holds the switch bar in contact with each of a pair of contacts 62 and 63. When depressed, the switch bar is adapted electrically to connect a pair of contacts 64 and 65. At 46 I have illustrated a switch which may be located in any convenient position and which is used 40 only in the event that it sometimes proves necessary or desirable to excite the electromagnet winding 22 from battery.

Now let us assume that the various elements of my starting equipment are in the 45 positions illustrated in the drawings and that the pedal switch 60 is depressed to start the engine A. As soon as the pedal is depressed, the electromagnet winding 20 is energized from battery 47 through a circuit 50 including conductor 48, switch contact 65, switch bar 60, switch contact 64, conductors 49' and 51 and thence through the electromagnet winding 20 to ground and back to battery. At this time the armature of motor D remains stationary, the motor circuit being open. As soon as the electromagnet winding 20 polarizes its core 19, the armature 23 is drawn toward core 19 and pinion 16 is caused to mesh with the teeth of flywheel B. This is readily accomplished by virtue of the fact that the opposed edges of the pinion and flywheel teeth are beveled as previously explained. As the sleeve 12 moves to the left (Figure 2), the ring XX 55 engages the rollers 39-39 and moves the connected ends of the arms of the snap-over mechanism to the left. At the instant that the pinion 16 has been moved completely into mesh with the flywheel teeth, the ring XX carries the rollers 39-39 to the left 70 (Figure 2) of a straight line passing through the rods 40-40. When this has occurred, the springs 44 quickly throw the conductor bars into engagement with switch contact blocks 26 and 27. The circuit of the 75 starting motor is now closed, said circuit being traceable from battery 47 through conductor 48, switch contact 65, switch 60, switch contact 64, conductor 49 and conductor 50 to one terminal of motor D, thence 80 through the motor, conductor 51' and the snap-over switch to ground. Power from the motor shaft is transmitted through coupling 11, shaft 10 and pinion 16 to the flywheel B. As soon as the engine A starts to 85 operate under its own power, the operator permits pedal switch 60 to return to its normal position, thus disconnecting battery from both the motor D and electromagnet winding 20. The pinion 16 being still in 90 engagement with the flywheel B, the engine now drives the dynamo electric machine D, the generated current traversing a circuit which may be traced from one terminal of the motor through conductor 51', 95 thence through electromagnet winding 22, thence through conductor 52 to switch contact 62, thence through switch bar 60 and contact 63 to conductor 50 and back to the motor. Electromagnet winding 22 polarizes its associated core 21 and the armature 23 is moved to the right (Figure 2), thereby 100 causing the pinion 16 to disengage the teeth of the flywheel.

As the armature 23 and sleeve 12 move to the right (Figure 2), the sleeve shoulder X engages and moves the rollers 39-39 of the snap-over mechanism. At the instant that the pinion has disengaged the flywheel teeth, the rollers 39-39 are carried to a 110 position to the right (Figure 2) of a vertical line passing through the rods 40-40. When this occurs, springs 44 quickly return the arms 33^a and 33^b of the snap-over mechanism to the positions illustrated in Figure 2.

The operation just described is repeated each time the engine is to be started.

If, for any reason, the engine should not start when the starting motor is energized, retracting electromagnet winding 22 may be excited from battery by closing knife switch 46.

Having thus illustrated and described a preferred embodiment of my invention, what I claim as new, and desire to secure by Letters Patent of the United States is:

1. Engine starting apparatus comprising a dynamo electric machine, a pinion in driven relation to said machine, said pinion

125
130

- adapted to be moved into and out of mesh with teeth carried by means fixed with respect to the crank shaft of the engine to be started, electromagnets for so moving said pinion, a snap-over switching mechanism controlling the circuit of said machine, said snap-over switching mechanism being operated by one of the aforesaid electromagnets, and being adapted to insure that said machine is supplied with electrical energy only when the teeth of said pinion are in mesh with their co-operating teeth, and a circuit for one of said electromagnets joined to the output terminal of said machine.
2. Engine starting apparatus comprising a dynamo electric machine, a pinion connected with the machine shaft, said pinion adapted to be moved into and out of mesh with teeth carried by means fixed with respect to the crank shaft of the engine with which the starting apparatus is associated, electromagnetic means for moving said pinion into mesh with its co-operating teeth, switching mechanism adapted to insure that electrical energy is supplied to said machine only when the teeth of said pinion are in mesh with their co-operating teeth, and a second electromagnetic means adapted when energized to disengage the teeth of said pinion from their co-operating teeth, said last mentioned electromagnetic means being excited by the current generated by said machine when, after the engine starts to operate under its own power, said machine is driven as a generator by the engine.
3. Engine starting apparatus comprising a dynamo electric machine, a pinion connected with the shaft of said machine, said pinion adapted to be moved into and out of mesh with teeth carried by means fixed with respect to the crank shaft of the engine with which the starting apparatus is associated, electromagnetic means for moving the pinion into mesh with its co-operating toothed means, and a second electromagnetic means adapted to shift said pinion out of engagement with its co-operating toothed means, said second electromagnetic means being excited by current created in said machine when, after the engine starts to operate under its own power, said machine is driven as a generator by the engine.
4. In combination, an engine having a toothed member in driving and driven relation to the crank shaft thereof, an electric motor, a pinion in driving and driven relation to said motor, and adapted to be shifted into and out of mesh with the aforesaid toothed member, a first electromagnetic means adapted when energized to move the pinion into mesh with its co-operating toothed member, a second electromagnetic means adapted when energized to withdraw the pinion from mesh with its co-operating toothed member, a battery, switching mechanism adapted when in one position to connect the first electromagnetic means in circuit with said battery, and
- adapted when in one position to cause the energization of the first electromagnetic means, and when in another position to cause the energization of the second electromagnetic means.
5. In combination, an engine having a toothed member in driving and driven relation to the crank shaft thereof, a dynamo electric machine, a pinion in driving and driven relation to said machine, and adapted to be shifted into and out of mesh with the aforesaid toothed member, a first electromagnetic means adapted when energized to move the pinion into mesh with its co-operating toothed member, a second electromagnetic means adapted when energized to withdraw the pinion from mesh with its co-operating toothed member, a battery, and switching mechanism adapted when in one position to cause said first mentioned electromagnetic means to be energized by said battery, and when in another position to place the second electromagnetic means in circuit with said machine for energization by current created in said machine when it is driven as a generator by the engine.
6. In combination, an engine having a toothed member in driving and driven relation to the crank shaft thereof, an electric motor, a pinion in driving and driven relation to said motor, and adapted to be shifted into and out of mesh with the aforesaid toothed member, a first electromagnetic means adapted when energized to move the pinion into mesh with its co-operating toothed member, a second electromagnetic means adapted when energized to withdraw the pinion from mesh with its co-operating toothed member, and switching mechanism adapted when in one position to cause the energization of the first electromagnetic means, and when in another position to cause the energization of the second electromagnetic means, together with switching means actuated by said electromagnetic means and adapted to insure that said motor is not supplied with electrical energy except when said pinion is in mesh with its co-operating toothed member.
7. In combination, an engine having a toothed member in driving and driven relation to the crank shaft thereof, a dynamo electric machine, a pinion in driving and driven relation to said machine, and adapted to be shifted into and out of mesh with the aforesaid toothed member, a first electromagnetic means adapted when energized to move the pinion into mesh with its co-operating toothed member, a second electromagnetic means adapted when energized to withdraw the pinion from mesh with its co-operating toothed member, a battery, switching mechanism adapted when in one position to connect the first electromagnetic means in circuit with said battery, and

when in another position to connect the second electromagnetic means in circuit with said machine for energization by current created in said machine when the latter is driven as a generator by the engine, together with a second switching mechanism operated by said electromagnetic means, said second switching mechanism adapted to insure that electrical energy is supplied to said machine from said battery only when said pinion is in mesh with its co-operating toothed member.

8. In combination, an engine having a toothed member in driving and driven relation to the crank shaft thereof, a dynamo electric machine, a pinion in driving and driven relation to said machine, and adapted to be shifted into and out of mesh with the aforesaid toothed member, a first electromagnetic means adapted when energized to move the pinion into mesh with its co-operating toothed member, a second electromagnetic means adapted when energized to withdraw the pinion from mesh with its cooperating toothed member, a battery, switching mechanism adapted when in one position to connect the first electromagnetic means in circuit with said battery, and when in another position to connect the second electromagnetic means in circuit with said machine for energization by current created in said machine when the latter is driven as a generator by the engine, together with a second switching mechanism operated by said electromagnetic means, said second switching mechanism adapted to co-operate with the first mentioned switching mechanism to connect the machine in circuit with the battery when said pinion has been moved into mesh with its co-operating toothed member.

9. In combination, an engine having a toothed member in driving and driven relation to the crank shaft thereof, a dynamo electric machine, a pinion in driving and driven relation to said machine and adapt-

ed to be shifted into and out of mesh with the aforesaid toothed member, a pair of electromagnets, the first one of said electromagnets adapted when energized to shift the 50 pinion into mesh with its co-operating toothed member, the second electromagnet adapted when energized to shift the pinion out of mesh with its co-operating toothed member, and a pair of switching devices, 55 one of said switching devices being under the control of the operator, the other switching device being operated by said electromagnets, actuation and restoration to normal of said operator controlled switch serv- 60 ing to excite the first electromagnet, to include the machine in circuit with the battery after the pinion is in mesh with its co-operating toothed member, to open the machine circuit, and to connect the second electro- 65 magnet in circuit with the machine for energization by current generated in the latter, when driven by the engine as a generator.

10. In combination, an engine having a 70 member in driving and driven relation to the crank shaft thereof, a starting motor, a member in driving and driven relation to said motor and adapted to be shifted into and out of operative engagement with the 75 first mentioned member, a first electromagnet adapted when energized to move the second member into engagement with said first member, a second electromagnet adapted when energized to withdraw said second 80 member from operative relation to said first member, a circuit for said second electromagnet, and means actuated incident to starting said engine for rendering the circuit of said electromagnet operative. 85

In witness whereof, I hereunto subscribe my name this 12th day of December, 1921.

ALLEN T. KIRK.
